CLAIM

The ornamental design for a handle for surgical stapler, as shown and described.

DESCRIPTION

FIG. 1 is a front perspective view of a handle for surgical stapler, showing our new design, with a rear screen in a first position;

FIG. 2 is a rear perspective view of the handle for a surgical stapler of FIG. 1, with the rear screen in the first position; FIG. 3 is a right elevational view of the handle for a surgical stapler of FIG. 1, with the rear screen in the first position; FIG. 4 is a left elevational view of the handle for a surgical stapler of FIG. 1, with the rear screen in the first position; FIG. 5 is a front elevational view of the handle for a surgical stapler of FIG. 1, with the rear screen in the first position; FIG. 6 is a rear elevational view of the handle for a surgical stapler of FIG. 1, with the rear screen in the first position; FIG. 7 is a top plan view of the handle for a surgical stapler of FIG. 1, with the rear screen in the first position; FIG. 8 is a bottom plan view of the handle for a surgical stapler of FIG. 1, with the rear screen in the first position; FIG. 9 is another front perspective view of the handle for a surgical stapler of FIG. 1, with the rear screen in a second position;

FIG. 10 is another rear perspective view of the handle for a surgical stapler of FIG. 1, with the rear screen in the second position;

FIG. 11 is another left elevational view of the handle for a surgical stapler of FIG. 1, with the rear screen in the second position;

FIG. 12 is another right elevational view of the handle for a surgical stapler of FIG. 1, with the rear screen in the second position;

FIG. 13 is another front elevational view of the handle for a surgical stapler of FIG. 1, with the rear screen in the second position;

FIG. 14 is another rear elevational view of the handle for a surgical stapler of FIG. 1, with the rear screen in the second position;

FIG. 15 is another top plan view of the handle for a surgical stapler of FIG. 1, with the rear screen in the second position; and,

FIG. 16 is another bottom plan view of the handle for a surgical stapler of FIG. 1, with the rear screen in the second position.

(Continued)

The handle portion shown in broken lines is unclaimed environment, and forms no part of the claimed design.
